UNITED STATES PATENT OFFICE

JOHN ROGER OLIVER, OF MEDFIELD, MASSACHUSETTS, ASSIGNOR TO REECE SHOE MACHINERY COMPANY, OF BOSTON, MASSACHUSETTS, A CORPORATION OF MAINE

PRESS OPERATING MECHANISM

Application filed June 23, 1927. Serial No. 200,904.

This invention is a novel press operating mechanism, and relates more especially to presses for cutting or punching sheet material, and the principles are herein shown applied illustratively to that type of press known as a clicker or clicking press adapted especially for dieing out leather or similar material to produce the constituent parts of various articles such as the uppers of boots and shoes.

A prior example of clicking machine is the Reece clicker as shown in Patent 1,228,834 to Schoenky of June 5, 1917, and the present invention is shown applied to a clicker generally of the type of the prior patent, to which reference may be made for certain details, for example the operating clutch, not herein fully shown. In a clicking machine a presser or head overhangs a flat bed and a 10 is operated by power to descend upon a loose die placed selectively upon the leather to cut out the desired shape, the presser or head being swingable laterally into and from position above the die so as to permit inspection 20 of the work between operations. With said prior patent the control pedal might be held depressed and the down and up operative movement of the head might be repeated. This disadvantage was to some extent avoided by the construction of a clicking press 25 shown in a later patent to Schoenky 1,295,931 of March 4, 1919 wherein the depression of the pedal brought about the closing of the clutch and at the same time the operation 30 of a latch, causing the immediate throwing out of the clutch and thereby the stoppage of the power shaft after a single revolution, so that the presser head was brought down 35 upon the die and lifted and brought to rest upon the die in its raised position.

The principal object of the present invention is to improve the mechanism and the operation by which, after the clutch is caused to be closed, in this case by a handle positioned upon the presser head, it will be positively opened and the machine thus brought to rest within a single rotation of the power shaft, notwithstanding any possible operation of the control handle, thus preventing repetition of cutting strokes.

Other and further objects and advantages of the present invention will be explained in the hereinafter following description of an illustrative embodiment thereof or will be understood by those skilled in the art.

To the attainment of the recited objects and advantages the present invention consists in the novel press and the novel features of operation, combination, arrangement and detail herein illustrated or described.

In the accompanying drawings Fig. 1 may be considered a left elevation of a clicking machine or press embodying the present invention, the operator being supposed to stand at the front of the machine, namely at the right side of the figure, for manipulation of the leather, the die, the presser head and the clutch controlling mechanism.

Fig. 2 is a top plan view of a detail portion of Fig. 1.

Fig. 3 is a horizontal section taken substantially on the line 3-3 of Fig. 1.

Fig. 4 is a rear elevation taken partly in section on the line 4-4 of Fig. 1.

Above the supporting legs 10 is firmly secured the main frame 11 which constitutes a support for the movable elements of the apparatus. Above the forward part of the frame is the bed or cutting block 12 clamped and held at the top of a solid supporting post 13 adjustable vertically by wheel 14 to adjust the bed with respect to the die and presser.

The swinging presser or head 15 is arranged to overhang the bed, and preferably this carries at its forward end an operating or control handle 16, which is available both for the bodily lateral swinging of the head to and from its position over the cutting die 17 and for the operative downward or cutting movement as will be described. The die 17 is preferably of the usual kind, placed by inspection on the material for each cutting operation.

The up and down movements of the presser head, in any swung position thereof, are preferably brought about and guided through an up and down sliding element 18 in the form of a plunger or post. The post 18 may be cylindrical and preferably reciprocates up and down with the presser, as in the prior patent,

but unlike the prior patent, the post 18 does not partake of the rotary or swinging movements of the presser. In other words the post reciprocates downwardly and upwardly in each operation and carries the presser head, but the post does not rotate, the presser head being mounted rotatably on the post to permit the swinging movements of the head.

The post or plunger 18, as usual, is arranged at the central rear portion of the machine, behind the cutting bed, and is shown engaged by the presser through an upper collar or rotary bearing 19 on the presser surrounding the post. The presser 15 is shown extended rearwardly behind the bearing 19 and downwardly at 20 to where it is formed into a lower rotary bearing 21 also surrounding the post; the presser 15, the bearings 19 and 21, and the extension 20 preferably constituting a single integral piece of metal.

The weight of the presser and connected parts may be supported through a thrust bearing 23 between the upper bearing 19 of the presser and a collar 24 adjustably clamped to the post.

In its upward and downward movements the post is guided by fixed slide bearings 27 and 28 constituting respectively upper and lower rearward extensions of the main frame 11. The post slides in these heavy rigid bearings. Its normal position is its raised position and its actuation is preferably through power connections at the base of the machine comprising a clutch and having connections to the lower end of the post to draw it forcibly downward and thrust it upward to normal position.

Referring to the power connections these may start with a pulley 30 rotated by a constantly running belt and heavy enough to constitute a fly wheel. The main or operating shaft 31 of the clicking press is normally disconnected from the pulley and is shown arranged in a central position extending fore and aft near the lower part of the press. Corresponding with said prior patent an eccentric 32 is shown mounted on the shaft. The lower end of the reciprocating post 18 is shown recessed so as to form a forked end 34 while an eccentric strap and rod 35, engaging the eccentric 32 is engaged also in the recess of the post and secured there by a cross pin 33, so that the eccentric movements are communicated as down and up movements to the post. The main shaft may revolve in fixed bearings at 36, the pulley normally turning freely on the shaft. The rear end of the shaft is shown as carrying a collar or enlargement 40 in which certain of the clutch elements are contained, as more clearly disclosed and described in the prior patent. Attached to an internal clutch dog is an outwardly extending pin 48 which is arranged to cooperate

with a shiftable shoe or cam 49. As seen in Fig. 1 the shoe 49 is in its rearward position and has cammed the pin 48 away from operative position so as to shift the internal clutch dog from operating position, thus 70 leaving the main shaft disconnected and stationary, while the fly wheel rotates. As explained in the prior patent it is only necessary to swing forwardly the cam shoe 49, thus disengaging the pin 48 and permitting 75 the engagement of the clutch, for a single rotation, the clutch being then disengaged if the cam shoe 49 has in the meanwhile been allowed to return to its normal position illustrated, and the shaft stopped. 80

The cam shoe 49 which controls the driving clutch may be adjustably mounted on a swinging member or arm 50 fulcrumed at 51 on a special bracket 52 standing rearwardly from the fixed bearing 28. The arm 85 50 has an upward extension 54 which may be operated, as will be described, for the restoration of the lever to normal position and the throwing open of the clutch, the extension 54 being positioned, for this purpose, beneath the lower bearing 21 of the presser head, so that in its descent this bearing strikes the extension and forces it downwardly to bring the lever to normal position. A spring 55 is arranged to pull forwardly on 90 the lever arm 50, thus tending to pull the cam shoe 49 away from operative position to allow the clutch to engage. The arm 50 carries a block 50^a formed with a notch or shoulder 56 and adjustable up and down on the arm. The shift lever is actuated by the presser to restore it to operative position rendering the clutch inoperative, namely by reason of the movement of the presser, and preferably during the downward or striking movement thereof. 105

The control of the described clutch may be best explained by commencing with the control handle 16 mounted at the forward end of the presser head 15. The handle 16 110 is interiorly apertured to engage slidably upon a pin 57 upstanding from the forward end of the presser head. By the dotted lines indicating pin and aperture the handle is shown to be in its upper position, ready to 115 be thrown down. It is to be understood that the handle is first used to bring the presser head over the die and is then thrown down to cause the operative or cutting movement of the head. The handle is shown formed with a groove 58 which is engaged by a fork 59 attached adjustably to a control lever 60. This lever is shown centrally pivoted through a sleeve 61 in which the lever can be 120 adjusted. The rear end of the control lever 60 is provided with a head 62, also adjustable on the lever, and this head containing a socket to receive the spherical head of a pin 63 outstanding from the head 64 of a downwardly extending rod 65, the head 64 being 125 130

in adjustable relation both to the pin 63 and to the rod 65. These various adjustments allow the parts to be set so that the axis of the ball and socket connection between the 5 control lever and the rod coincides with the axis of swinging of the presser head, namely the center line or axis of the post 18, thus allowing for lateral movements of the head without interfering with the control movements 10 of the handle, the lever and the rod. These features in connection with the arrangement of the lifting rod 65 in a vertical slot or runway at the forward side of the post 18 constitute a highly convenient and effective 15 mode of transmitting the controlling movement from the handle 16 to the clutch operating elements at the base of the machine. The described arrangement is superior to any other arrangement in that the 20 lift rod 65 does not partake of the swinging movement and in fact only the handle 16 and the control lever 60 and the parts rigidly connected with them swing laterally with the presser head.

25 The lower end of the lift rod 65 is shown extending into a cutaway recess in the lower fixed bearing 28, at which point the rod is provided with a horizontal offset or sleeve and pin 66 which in turn is connected by a 30 downward rod 67 to a second horizontal offset 68, best shown in Fig. 3, this in turn being connected with a swinging lever 69 fulcrumed at 70 to a fixed bracket or extension of the frame. Thus when the handle 35 16 is thrust down this lifts the forward end of the lever 69 which swings about its fulcrum 70.

This movement of the lever 69 by the control handle 16 may control the clutch as follows. A bell crank lever is shown mounted on the same fulcrum 70 as the swinging lever 69, this bell crank consisting of a rearwardly extending arm 72 and a downwardly extending arm 73, both of which at certain times 45 constitute substantially a rigid part of the lever 69, so that when the lever is swung upwardly the bell crank arm 72 will be swung downwardly. The arm 50 which carries the clutch cam shoe 49 is shown formed with a shoulder or notch 56 normally engaged by the bell crank arm 72 as indicated. The spring 55 spans the space from the arm 50 to the bell crank arm 73 and thus tends to hold both of these elements in the position illustrated, with the bell crank arm 72 engaged in the notch 56. It is only necessary to depress the arm 72 and shift it out of the notch 56 to allow the spring 55 to pull on the arm 50 and thus remove the cam shoe 49 and permit the closing of the clutch, and this is herein effected by the lifting of the lever 69. In order to convey the motion of the lever 69 to the bell crank there is shown a hook or finger 60 65 pivoted on the lever 69 and having its lower rearward hook end engaged under the

bell crank downward arm 73, so that the lifting of the lever 69 pulls upon the bell crank, the whole system swinging as a unit. A slight normal clearance is shown between the hook of the finger 74 and the bell crank arm 73, in order to insure the resetting of the parts at a subsequent stage. The hooked finger 74 is normally held in its illustrated position through the tail 75 of the finger, pulled downwardly by a spring 76. This spring 75 may have substantial length and strength and as arranged serves the double purpose of pressing the finger toward normal position and of pulling down on the lever 69 thus lifting the control handle 16, which has to be 80 pressed downwardly by the workman in opposition to the spring 76.

It will be understood that as soon as the handle 16 is thrown down and the lever 69 thus swung upwardly the bell crank arm 72 85 will be thrown downwardly thus disengaging the notch 56 and permitting the cam shoe 49 to be retracted, and the clutch engaged. The rotation of the main shaft thereupon starts, and the post 18 and presser head are drawn downwardly by the eccentric 32. During the downward movement and before the parts start upwardly the following operations are performed in a positive manner, beyond the control of the workman. The lower bearing 21 of the presser head strikes and depresses the upward extension 54 of the lever 50 carrying the cam shoe 49. This throws the cam shoe rearwardly into operative position for stopping the main shaft at 90 the end of a single rotation. It is necessary however to latch the arm 50 in this position otherwise it would again retract on the subsequent lifting of the presser head. For this purpose the hooked finger 74 is arranged to 105 be depressed during the downward movement of the presser head, so as to release the bell crank arm 73, the spring 55 thereupon throwing upwardly the bell crank arm 72 to reengage the notch 56 and lock the arm 50 110 rearward in normal position. This may be effected by a lug 78 outstanding from the lower part of the post 18. This lug is preferably a separate piece having upper and lower stems 79 and 80 inset into the post. As 115 will be clear from Fig. 1, the lug 78 does not strike the hooked finger 74 until the latter part of the descending movement. It is so timed as to depress the finger and release the bell crank so that the latter will be sprung 120 into normal position to engage the notch 56 as the lever 50 is thrust rearwardly through the descent of the presser head. The upward movement of the presser head and connected parts operates to restore the various levers, 125 fingers, arms, etc., to the normal positions shown.

The characteristics of the invention may be more clearly explained. The lever 50 is a clutch shifter, shown in normal position 130

where it has caused the opening of the clutch and the stoppage of the shaft with the presser and post elevated. Its shoulder 56 is in the nature of a detent, and is engaged by the arm 5 72 which may be described as the latch of the clutch shifter, the word latch used broadly to include any mechanical device which when thrown brings about the shift of the shifter and when restored locks or holds the shifter 10 in its inoperative position against the pull of spring 55. The arm 69 which causes the throw of the latch 72 may be considered as the operating arm of this lever system, and it may be moved upward in any manner to 15 throw down the latch; and as this is the clutch shifter releasing action the arm may be considered as the releaser, or release lever. The hook or finger 74 between the two arms 69 and 72 is representative of any trip or connection 20 which conveys the swinging motion but which may be operated or tripped for operatively disconnecting the arms, so that the restoration of the latch is beyond the interference of the workman. In one aspect the 25 control handle 16 is operatively a part of the operating arm 69, as they always move together.

There has thus been described a press for cutting or punching sheet material embodying the principles and attaining the objects 30 of the present invention. Various matters of operation, combination, arrangement and detail may be modified without departing from the principles and therefore the invention 35 is not intended to be limited to such matters except so far as set forth in the appended claims:

What is claimed is:

1. In a control mechanism for clicking or other power presses of the class having a reciprocable post carrying a presser, power means for moving the post down and up comprising a clutch, a clutch shifter for putting the clutch into and out of operation for causing the descent and rise of the presser, and having a tendency toward inoperative position wherein it renders the clutch operative, and control means for the clutch shifter comprising a latch normally holding the shifter operative and therefore the clutch inoperative, such latch having a tendency toward latching position, a releaser for throwing the latch having a trip engaging the latch, and means actuated by the descent or rise of the post for restoring the shifter to operative position and for throwing the trip to permit the latch to re-engage the shifter. 55

2. In a control mechanism for power presses of the class having a reciprocable post carrying a presser, power means for moving the post down and up comprising a clutch, a clutch shifter for putting the clutch into and out of operation for causing the descent and rise of the presser, and control means 60 for the clutch shifter comprising a latch nor-

mally holding the shifter operative and therefore the clutch inoperative, a spring device pressing the shifter toward inoperative position, a releaser for throwing the latch having a trip engaging the latch, a spring device 70 pressing the latch toward latching position, and means actuated by the movement of the presser post for restoring the shifter to operative position and for throwing the trip to permit the latch to re-engage the shifter. 75

3. A press as in claim 1 and wherein the means actuated by the movement of the post comprises contacts moving with the presser, one arranged to restore the shifter back to 80 position, and the other to throw the trip and permit the latch to re-engage the restored shifter.

4. In a control mechanism for power presses of the class having a reciprocable post carrying a presser, power means for moving the presser post down and up comprising a clutch of the type having a shifter which when shifted to inoperative position causes the power to engage and drive the press and 85 when shifted to operative position causes the clutch to disengage and the press to stop at a definite position with the presser post raised, means normally pressing the shifter yielding into inoperative position, a latch 90 normally holding the clutch shifter in operative position, means yielding pressing the latch to normal position, release means operable at will for throwing the latch and thereby engaging the clutch to cause a down 95 and up reciprocation of the presser post, such release means including a device holding the latch in such position, and means actuated by such movement of the presser post to restore the shifter to operative position and 100 to cause the device to release the latch and so permit the latch to relatch the shifter. 105

5. In a control mechanism for clicking presses of the class having a reciprocable post carrying a presser, power means for moving the post downward and upward comprising a clutch, a clutch shifter for putting the clutch into and out of operation for causing the descent and rise of the presser post, and control means for the clutch shifter comprising a latch normally holding the shifter operative and therefore the clutch inoperative, a releaser for throwing the latch and having a trip, and means actuated by the movement of the post for restoring the shifter to operative position and for throwing the trip to permit the latch to re-engage the shifter. 115 120

6. In a control mechanism for power presses a clutch, a shifter therefor having a latch shoulder, and a lever system for controlling the shifter, comprising a swinging latch arm engaging said shoulder, an operating arm, and a trip hook pivoted on one 125 of said arms normally engaging the other 130

arm, so that said lever system moves as a whole when the operating arm is thrown and the latch arm moves to release the shifter, close the clutch and actuate the press, and means operating at a definite time to restore the shifter and to throw the trip hook to cause the latch arm to be restored and re-engage the shifter shoulder.

7. A power control mechanism for presses as in claim 6 and wherein the restoring means comprises contacts moving with the operative movement of the press and operating positively to prevent repeat operation of the press upon one throw of the operating arm.

15 In testimony whereof, I have affixed my signature hereto.

JOHN ROGER OLIVER.
